(57) **CLAIM**

The ornamental design for a gaming machine with graphical
user interface, as shown and described.

DESCRIPTION

FIG. 1 is a front perspective view of a gaming machine with
graphical user interface showing our new design;
FIG. 2 is a front perspective view thereof with the shading
on the screen omitted for clarity purposes;
FIG. 3 is a top view thereof;
FIG. 4 is a right view thereof;
FIG. 5 is a rear side view thereof;
FIG. 6 is a left side view thereof;
FIG. 7 is a top view thereof; and,
FIG. 8 is a cross-section view thereof taken through line 8-8
of FIG. 7.

The broken lines depicting the remainder of the gaming
machine illustrates environmental structure and form no part
of the claimed design. The curved oblique line shading
shows that the surface is a transparent, translucent, highly
polished or reflective surface.
